EXPLOSIVE DEVICE FOR USE IN FIRE FIGHTING EQUIPMENT SYSTEMS AND THE LIKE

Anders Mathisen, Isleworth, England, assignor to Graviner Manufacturing Company Limited, Isleworth, Middlesex, England, a British corporation

Application May 13, 1944, Serial No. 535,508
In Great Britain May 3, 1943

7 Claims. (Cl. 137—139)

1

This invention relates to improvements in explosive devices of the kind adapted to use in fire-fighting equipment systems, fire-extinguishing apparatus, electrical switch devices and for similar purposes.

In order to obtain actuation of apparatus parts and appliances in fire-fighting systems and the like it has been proposed to use small explosive charges in the discharge heads of fire extinguishers and the like, and to ignite such charges by small electrically ignited fuses capable of energisation by closure of electrical switch devices such as manually operated push button switches, flame or fire detecting switches, and crash or inertia and gravity element operated switch devices and the like.

The object of the present invention is to provide a compact explosive device capable of ignition, preferably by electrical means but if desired also by percussion means, whereby a mechanism actuating or securing member is capable of displacement by an explosive charge to effect required operation of apparatus, mechanical or electrical devices and the like.

To this end the present invention consists in an explosive device comprising a tubular member to which a stud member is secured by means of a frangible rim, a closure member being adapted to be inserted into the tubular member to form an explosive substance containing chamber between one end of said stud and said closure member, means being provided for igniting said explosive substance to displace the stud member.

The closure member may be provided with a longitudinal fine bore conduit, and an electrically energised fuse mounted for example in a suitable metallic fuse holder adapted to be secured in the tubular member, may be provided for igniting the said explosive substance through the conduit.

The closure member is preferably provided with a projection adapted to protrude into said explosive substance, the fine bore conduit terminating in a blind end in said projection, one or more fine holes being produced transversely in said projection so as to connect with said conduit, ignition of the explosive substance being effected through said conduit and hole or holes in a substantially central position in the mass of explosive substance.

2

In one form of the invention, the tubular member may be provided with a restricted bore in one end into which said stud member is adapted to fit, a thin rim being then provided upon the stud member which rim fits inside the tubular member so as to abut against the end of the restricted bore portion of the tubular member.

In one form of the invention, the rim of the stud member and the closure member may be spaced by a sleeve adapted to form the explosive containing chamber, and said sleeve and the closure member may be screw-threaded so as to be secured together. In this form of the invention the rim of the stud member may be secured to said sleeve by soldering, brazing or the like so that these parts form an explosive containing chamber capable of insertion into the tubular member, in which they may be secured by the metallic ignition device holder member, which member may serve to lock the parts firmly in position.

While the ignition means may be in any desired form such as a percussion device, preferably an electrically ignited fuse is secured in said ignition device holder, said fuse comprising an electric current heated element and an ignition compound substance adapted to ignite said explosive substance through the said conduit and holes in the closure device.

The device of the present invention has numerous applications and in one form the tubular member may be in the shape of a cap device adapted to be secured in a fluid cock device body, the stud member being adapted to engage a cock shut-off plug arranged to close the said cock against fluid flow upon ignition of said explosive substance.

As the force which can be applied to the thin rim of metal upon the stud is limited, the tubular member may be secured, for example, in a housing, and the stud may be elongated and disposed transversely across a space in said housing in which said transversely disposed stud may serve as an abutment for an actuating member arranged to operate any type of mechanism, the force applied by said actuating member being therefore taken by a thrust at right angles to the axis of the stud which does not apply force to the rim.

In a delay action electric switch device the tubular member may be secured to a fuse holder

containing a delay action fuse, the stud member engaging electric switch actuating mechanism adapted to operate electric contacts upon ignition of said explosive substance at a predetermined time delay after electric ignition of said fuse.

The invention will now be described with reference to the accompanying drawings which show embodiments of the invention by way of example and in which:

Figure 1 shows a longitudinal view of the device with parts in section,

Fig. 1—A shows a simplified construction omitting the retaining sleeve,

Fig. 1—B is another view of the simplified construction of Fig. 1—A,

Fig. 1—C is a longitudinal sectional view of the tubular member or casing of the construction of Fig. 1, showing the terminal restricted bore,

Figure 2 is an exploded view showing the unit of Fig. 1 with parts in juxtaposition,

Figure 3 shows a slightly modified form of the device shown in Figure 1 applied to an appliance in the form of a liquid shut-off cock,

Figure 4 shows another application of the device shown in Figure 1, this being shown in normal unoperated position,

Figure 5 is a similar view to Figure 4, shown in the operated position and

Figure 6 shows another modified form of device shown in Figure 1 applied to an electric switch appliance.

Referring now to Figures 1 and 2, numeral 2 denotes a tubular member having a terminal restricted bore 12 to which the stud member 3 is secured by means of a frangible rim 4.

A closure member 5 is adapted to be inserted into member 2 to form a chamber for containing explosive substance 6, and an electrically ignitable fuse 7 comprising electric current heated element 44 secured in a fuse holder 8 is screwed into member 2 to secure parts 3 and 5 in appropriate position in member 2 to form a chamber for explosive 6.

Closure member 5 is provided with a longitudinal fine bore conduit 9 as shown in Figure 1.

As shown in the construction shown in Figure 1 and Figure 2, the closure member 5 is provided with a projection 10 in which one or more transverse fine bored holes 11 are provided the effect of which is that when fuse 7 is ignited, an ignition flame travels down conduit 9 and is deflected through holes 11 to ignite explosive substance 6 practically in the center of said substance thereby increasing the explosive effect. At the end of closure member 5 which is opposite projection 10, fine bore conduit 9 terminates in a small conical recess which is adapted to receive fuse 7 and conduct the ignition flame therefrom.

On occurrence of the explosion, the gas pressure passes back through holes 11 of which there may be one, two or four, these holes being preferably oppositely disposed so that the gas pressure streams strike in opposite directions into conduit 9 in which they are deflected at right angles back through conduit 9, the effect of which is to reduce loss of gas pressure and thereby risk of blow back.

In order that reliability of operation shall be obtained, it has been found necessary to make rim 4 approximately .018" thick if stud 3 is of brass.

Conduit 9 may be of the order of .030" diameter whereas holes 11 are generally .015" diameter, the quantity of explosive substance being between 3 to 5 grains of fine grain gunpowder.

In the simplified form of construction shown in Fig. 1—A and Fig. 1—B wherein the explosive substance 6 is contained between the walls of the bore of tubular member 2 and stud 3 and closure member 5, and frangible rim 4 of stud 3 is formed integrally in one piece with tubular member 2, there is risk during handling and assembly of fracturing rim 4, and for that reason the more rugged construction shown in Figure 1 is preferred and in this form of Figure 1 the member 2 is provided with a restricted bore 12 (Fig. 1—C) into which a portion of stud 3 fits reasonably tightly, rim 4 fitting internally in sleeve 2 so as to retain stud 3 therein.

As shown in the form of Fig. 1, rim 4 of stud 3 and closure member 5 may be spaced from one another by a sleeve 13, this being adapted to fit into member 2, a part of the closure member 5 and the sleeve 13 being screw-threaded so as to be secured together.

In this form employing sleeve 13, rim 4 is secured to sleeve 13 by soldering, brazing or the like so that the parts 3, 4, 5 and 13 form a chamber for containing explosive substance 6, the unit being capable of insertion into tubular member 2, in which it is secured by metallic holder 8 of fuse 7, so that when an explosion occurs, stud 3 will be blown out by the explosive force, rim 4 being shorn off due to its contact with the restricted bore portion 12 of tubular member 2, as will be clear by reference to Figures 4 and 5.

Referring now to Figure 3, which shows an application to a valve, of the type of explosive unit shown in Fig. 1, 14 denotes a fluid cock device body into which a tubular member in the form of a cap device 22 is secured, stud 3 being screwed into a shut-off plug 15 which is secured against the end of cap device 22 by a liquid excluding washer 16.

Upon electrical ignition of fuse 7, stud 3 will be blown out and plug 15 blown across the cock body plug seating 17 where it is retained by a compression spring 18 which expands to retain plug 15 in the liquid shut-off position.

Referring to the modification of Figs. 4, 5, as applied to an explosive releasable spring actuated control unit, since the force which can be applied to rim 4 is limited, the tubular member 2 may be shaped in a modified form as shown at 23, Figures 4 and 5, in which case it can be secured in a housing 19 which has a transverse portion or tube 20 integral therewith or secured thereto by welding as shown at 21.

Stud 33 (Figs. 4 and 5) is in this case elongated compared to stud 3 of the form of Figs. 1—3, and is disposed transversely across the open space in said housing, and a spring urged actuating member 24 is disposed in the space in said housing portion or tube 20 to which it is secured by stud 33 which engages holes 25 in member 24. By this means actuating member 24 can be displaced under action of spring 26 when explosive material 6 blows stud 33, less rim 4, into cavity 27 in housing 19 as shown in Figure 5.

As will be seen, the thrust due to spring 26 is taken by stud 33 in a transverse direction and is not applied to rim 4, and for this reason considerably greater force can be applied to stud 33 than could be applied longitudinally to stud 3, as there would be risk of shearing the thin rim 4 if excessive force is applied to the rim.

Referring now to the modification of Figure 6, applied to an electric switch, stud 3 engages an arm 28 hinged on pin 29 which pin also supports a contact actuating member 30 which engages

a movable contact spring 31 adapted to open or close electric circuits by means of spring contact points 32, one of which is secured to a semi-rigid spring contact 34.

As shown in Figure 6, contact points 32 are normally open and a tubular member shaped as shown at 222 engages a metallic holder 35 which encloses a delay action fuse 36 from which it is spaced by insulation sleeving 37.

In the particular construction shown in Figure 6, fuse 36 has a delay of ten seconds, that is to say that when fuse 36 is electrically energised it burns for ten seconds before explosive substance 6 is ignited. By this means a time lag of the switch device is obtained.

The explosive device and the switch mechanism shown in Figure 6 is enclosed in metallic or plastic material casing 38 to which fuse holder 35 is secured by bracket and screw means 39, contacts 31 and 34 being secured to lid 40 of casing 38 by securing bolts, insulation sleeving and spacers in known manner, electrical connections 41 being taken from contacts 31 and 34 to terminals 42 in an insulation terminal block device 43 of known form.

Fuse 7 comprises an electric current heated element 44, see Figure 2, which is connected to electric leads 45, which leads are connected to terminals 46 in a terminal block device 47 of known form.

For use in a fire-fighting system upon aircraft, for example, the switch device appliance shown in Figure 6 may be employed to introduce a time lag between the energization of fuse 36 due to operation of a control switch which is operated on occurrence of a fire and the discharge of electrically energised fire-extinguishing appliances which are controlled by closure of switch contacts 32.

In order to provide means for checking circuit continuity over contacts 32, an insulating cam 48 mounted upon spindle 49 is provided, said cam being operable externally from the casing and being spring operated to bring this back into normal position as shown in Figure 6.

In order to permit escape of explosive gases from casing 38 when closed by lid 40, a disc 50 is pressed into a recess 51 in casing 38, which disc is struck by stud 3 upon ignition of explosive substance 6 to displace the disc whereby the gases escape through an orifice 52 in casing 38.

As will be appreciated, the device of the invention constitutes a form of relay, in which a small electric current generally of the order of $\frac{1}{2}$ ampere is sufficient to effect displacement or operation of a mechanical device requiring considerable force, by use of a small quantity of explosive substance.

By this means the appliance of the invention has considerable advantages over electromagnetic relay and like devices which would require heavy currents for effecting operation of mechanical appliances requiring comparable force, and by this means a considerable reduction in weight is obtained in appliances as shown in Figures 3 to 6, which is important when these appliances are employed in fire fighting equipment for use upon aircraft.

Having thus fully described my invention, what I claim as new and desire to protect by Letters Patent is:

1. An explosive device comprising in combination a tubular member in the form of a cap device, a stud member secured to said tubular mem-

- ber by a frangible rim, a closure member adapted to be inserted in said tubular member, said tubular member defining an explosive substance containing chamber between one end of said stud and said closure member, means for igniting said explosive substance to displace said stud member, a fluid cock device body, means for securing said tubular member in said body, a shut-off plug, means for securing said plug to said stud member, said fluid cock device body having a plug seating recess, and means for retaining said plug in said seating recess after displacement of said stud member by ignition of said explosive substance.
15. 2. In an explosive actuatable valve comprising a valve seat and a bonnet, a plug, means in said bonnet for guiding said plug into tight engagement with said valve seat, an explosive unit comprising a mounting terminal portion and a projectile terminal portion and a chamber containing explosive material interposed between said terminal portions, said projectile terminal portion being rigidly mechanically connected to said chamber only by a frangible rim, said explosive unit further comprising means for igniting said explosive material, said mounting terminal portion being fixedly mounted in said bonnet, said projectile terminal portion being rigidly mechanically connected to said plug and being directed in the direction of the path of said plug to said valve seat, whereby ignition of said explosive material fractures said frangible rim and propels said plug along said guiding means into tight engagement with said valve seat.
35. 3. A valve as set forth in claim 2, said bonnet further comprising a helical spring mounted to urge said plug outwardly from said bonnet and upon projection of said projectile terminal portion to hold said plug in tight engagement with said valve seat.
40. 4. In an explosive actuatable valve comprising a valve seat and a bonnet, a plug, means in said bonnet for guiding said plug into tight engagement with said valve seat, an explosive unit fixedly mounted in said bonnet and comprising a sleeve, a stud member comprising a frangible rim by which it is fixedly attached to one end of said sleeve, a closure member fixedly attached to the other end of said sleeve, said sleeve and said stud member and said closure member defining an explosive chamber, explosive material in said chamber, said closure member comprising a bore communicating with said chamber, a fuse mounted extending into said bore, said bonnet comprising mounting means for fixedly mounting said stud member and said sleeve and said closure member as a unit in said bonnet, said mounting means comprising a shoulder in engagement with said frangible rim, and a rigid direct mechanical connection between said stud member and said plug, whereby ignition of said explosive material fractures said frangible rim and propels said plug along said guiding means into tight engagement with said valve seat.
55. 5. A valve as set forth in claim 4, said bonnet further comprising a helical spring mounted to urge said plug outwardly from said bonnet and upon projection of said stud member to hold said plug in tight engagement with said valve seat.
60. 6. An explosive actuatable valve as set forth in claim 2, said projectile terminal portion and its said frangible rim being formed integrally with said chamber and said frangible rim constituting an integral connection between said

projectile terminal portion and said chamber.
 7. A device as recited in claim 4, the end of said bore communicating with said chamber terminating in a conical recess flaring outwardly toward said chamber, and said fuse being mounted with a portion thereof extending into said conical recess.
